UNITED STATES PATENT OFFICE.

HARRY G. JENNISON, OF TOLEDO, OHIO.

WOOD-PAVEMENT.

1,061,296.

Specification of Letters Patent. Patented May 13, 1913.

Application filed April 17, 1912. Serial No. 691,439.

To all whom it may concern:

Be it known that I, HARRY G. JENNISON, a citizen of the United States, residing at Toledo, Lucas county, Ohio, have invented 5 new and useful Wood-Pavements, of which the following is a specification.

This invention relates to foothold provision and expansion take up features of pavement.

10 This invention has utility when embodied in a wood block pavement.

Referring to the drawings: Figure 1 is a transverse fragmentary view of a pavement embodying the invention; Fig. 2 is a plan 15 view thereof; Fig. 3 is a perspective view of one of the blocks; and Fig. 4 is a fragmentary view showing the expansion take up.

Between the curbs 1 are disposed the blocks 2 having the upper face thereof expose 20 the end of the grain of the wood, the blocks being laid to break joints. On one of the sides of the blocks herein shown as a longer side are integral extensions or parallel ribs 3, while upon an adjacent vertical 25 side is shown a similar vertical rib or extension 4. These integral ribs 3 and 4 are of such minor extent as to the blocks as to provide spacing means between the blocks affording desirable foothold for horses and 30 thus rendering the pavement less slippery, especially when impregnated with a preservative say some hydrocarbon product.

In the laying of the blocks as shown in Fig. 2, the transverse expansion or take up is 35 taken care of by the spacing extensions 4 while the longitudinal expansion take up is cared for by the extensions or ribs 3. In practice as these ribs 3 are subjected to compression strain due to expansion of the block 40 on account of temperature change or variation in moisture content, they are crushed or reduced in size as shown by ribs 5 in Fig.

4, while the similar action as to the transverse expansion take up acts upon the ribs 4 to crush them as shown in rib 6, Fig. 4. 45 Accordingly by the laying of these blocks 2 upon a concrete or other proper foundation there is an open-work pavement with crushable ribs integral with the blocks disposed in spacing relation therebetween, 50 which spaces may be filled with tar or sand if desired. The crushable or compressible nature of the wood, is such that upon release of the strain, there may be some recovery tending toward original spaced relation—in 55 practice, an elasticity is thus given to the pavement grouping over that of block pavement having the sides directly abutting. In this rectangular block structure, the lines of expansion are taken care of most effectively 60 in the two directions perpendicular to each other.

What is claimed and it is desired to secure by Letters Patent is:

1. A pavement comprising wood blocks 65 with the grain of the wood of the blocks extending in one direction, there being wood spacing means for the blocks having the grain of the wood of the spacing means extend in the same direction as the grain of the 70 wood of the blocks.

2. The combination with a wood paving block provided with an integral wood projection extending in the direction of the grain of the block along a vertical side of the 75 block, of a second block spaced from the first by said projection.

In testimony whereof I hereunto set my hand in the presence of two witnesses.

HARRY G. JENNISON.
